UNITED STATES PATENT OFFICE.

SEBASTIANO MARZOCCIO, OF NEW YORK, N. Y.

GAS-BURNER.

1,261,418.

Specification of Letters Patent.

Patented Apr. 2, 1918.

Application filed March 24, 1917. Serial No. 157,072.

To all whom it may concern:

Be it known that I, SEBASTIANO MARZOCCIO, a citizen of the United States, residing at the city of New York, borough of 5 Manhattan, in the county and State of New York, have invented certain new and useful Improvements in Gas-Burners, of which the following is a full, clear, and exact specification.

10 This invention relates to improvements in stoves and ranges, and the like, adapted to be operated by a fluid fuel, and the same has for its object more particularly to provide a burner for the fuel which will be 15 economical in its operation and simple in its construction.

Further, the invention has for its object 20 to provide a burner comprising a plurality of mixing chambers provided with means for admitting a fluid fuel to any of the mixing chambers independently of the others thereof.

Further, the invention has for its object 25 to provide a plurality of units or sections comprising a mixing chamber and pipes communicating therewith together with means for admitting a fluid fuel to the mixing chamber whereby burners of different sizes may be formed by the assembling of 30 two or more of the units or sections.

Further, the invention has for its object 35 to provide a stove or range of this type with heat-retaining members which are so supported within the fire-pot that their weight is not borne by the burner.

Further, the invention has for its object 40 to provide a stove or range of this type with heat-retaining members which are so supported within the fire-pot that they are all positioned above the outlet openings of the pipes of the burner.

Other objects will in part be obvious and in part be pointed out hereinafter.

To the attainment of the aforesaid objects 45 and ends, my invention consists in the novel details of construction, and in the combination, connection and arrangement of parts hereinafter more fully described and then pointed out in the claims.

50 In the accompanying drawing showing two illustrative embodiments of the invention—

Figure 1 is a front view of a range with the improved burner applied thereto, parts 55 being broken away;

Fig. 2 is a sectional view taken on the

line 2—2 of Fig. 1, part of the heat-retaining members being removed;

Fig. 3 is a sectional view taken on the line 3—3 of Fig. 1, and

60

Fig. 4 is a perspective view of one of the sections or units of a modified form of burner.

While the improved burner may be used 65 in connection with any suitable type of stove or range, it is shown, for purposes of illustration, as applied to a French range.

Referring to the drawing 10 indicates 70 a range having a fire-pot 11 located between ovens 12, 12, as is usual in French ranges. Positioned within the fire-pot 11 and supported in any suitable manner, as for example, by brackets 13 is the burner.

As shown in Figs. 1, 2 and 3 the burner 75 comprises a hollow casting 14 provided with a plurality of longitudinally extending partitions 15 forming a plurality of mixing chambers 16 arranged side by side. As shown the casting 14 has five mixing chambers 16 formed therein but it is, of course, 80 understood that this number may be varied without departing from the spirit of the invention.

The upper wall of each of the mixing 85 chambers 16 is provided with a plurality of outlet openings arranged in a row and extending longitudinally thereof, and the lower wall of each mixing chamber 16 is provided with an inlet opening 18.

Communicating with the outlet openings 90 of the mixing chambers 16 and extending upwardly therefrom are a plurality of rows of pipes or nozzles 19, 20 and 21. The pipes 19, communicating with the outlet openings of the central mixing chamber, are straight 95 and their upper ends terminate below the top plate of the range a sufficient distance to form a space between the top plate and the ends of the pipes for a purpose herein-after described. The pipes 20, communicat- 100 ing with the intermediate mixing chambers 16', are of the same height as the pipes 19 and are provided, intermediate their ends, with laterally and upwardly extending branches 20' the upper ends of which are 105 in the plane of the upper ends of the pipes 19 and 20, and are preferably spaced from the upper ends of the pipes 20 a distance equal to the distance between the upper ends of the pipes 19 and the upper ends of the 110 pipes 20. The pipes 21, communicating with the outer mixing chambers 16, are of

less height than the pipes 19 and 20 and their upper portions are inclined outwardly and terminate adjacent the walls of the ovens 12, 12 in order to direct the flame 5 thereagainst.

22 indicates a gas pipe leading from a suitable source of gas supply and provided with branch pipes 23 communicating with the air supply pipes 24 having their inner 10 ends connected to the inlet openings 18 of the mixing chambers 16. The branch pipes 23 are provided with valves 24' to control the flow of gas therethrough and the pipes 24 are provided with regulating valves of 15 any suitable type to regulate the amount of air passing therethrough.

Supported above the upper ends of the pipes 19 and 20 in any suitable manner, as by brackets 25, is a grid or grate 26 having 20 the openings thereof registering with the upper ends of the pipes 19 and 20 and the branches 20'. The space between the grate 26 and the top plate of the range is filled with a plurality of heat-retaining members 25 27, of any desired form, made of fire-brick, fire-clay, lava, or any other suitable refractory material. The heat-retaining members 27 conserve and store the heat from the flame, thereby effecting a saving in the 30 amount of gas consumed during the use of the range, and as all of the members 27 are positioned above the burner they will all be heated to substantially the same extent.

Referring to Fig. 4 illustrating a modification of the invention, 28 indicates one 35 of a plurality of units or sections of which the burner is composed. Each unit or section comprises a mixing chamber 29 provided with a plurality of pipes 30 extending 40 upwardly from its upper surface and communicating with the interior thereof. Fluid fuel is supplied to the mixing chamber 29 of each section or unit 28 through an inlet opening 31 in its lower wall in the manner 45 above described. While the pipes 30 of the section shown in Fig. 4 are similar to the pipes 19 associated with the central mixing chamber 16 of the burner shown in Figs. 1, 2 and 3 it will, of course, be understood that 50 other units or sections may be provided having pipes similar in construction to the pipes 20, and 21 associated with the intermediate and outer mixing chambers of the burner shown in said figures. The sections 55 or units 28 of the burner are placed side by side and the number of units or sections employed in any instance to form a burner will, of course, depend upon the width of the fire-pot of the stove or range in which 60 the burner is to be installed.

In operation if the maximum amount of heat is required for cooking or other purposes, all of the pipes 19, 20 and 21 of the burner are utilized. If the ovens 12, 12 are 65 not to be used, but the maximum amount of

heat is required at the top plate of the range the pipes 19 and 20 are utilized, whereas if only a moderate heating of the top plate is desired the fuel supply to one or more of the rows of pipes 19 and 20 may be cut 70 off by closing the appropriate valve or valves 24 and the remaining row or rows utilized thereby effecting a saving in the consumption of gas. In either instance a further saving of gas may be effected by 75 cutting off the supply to one or more of the rows of pipes 19 and 20 after the heat-retaining members 27 have become thoroughly heated as they retain the heat that they have absorbed for a considerable period of 80 time.

Should it be desired to use only one or both of the ovens, one or both of the rows of pipes 21 are utilized thereby insuring that none of the gas being consumed by the 85 burner will be wasted.

Having thus described my said invention what I claim and desire to secure by Letters Patent is:—

1. A burner comprising a plurality of 90 contiguous mixing chambers having pipes communicating therewith and extending upwardly therefrom, the pipes communicating with certain of said mixing chambers being of less height than the pipes communicating 95 with the other of said mixing chambers and having their upper portions extending outwardly, each of said mixing chambers being provided with means for admitting fluid fuel thereto, substantially as specified. 100

2. A burner comprising a plurality of contiguous mixing chambers, pipes communicating with certain of said mixing chambers and having their upper portions extending outwardly, and pipes communicating with the other of said mixing chambers and being of greater height than said first-mentioned pipes, certain of said second-mentioned pipes being provided with branches, each of said mixing chambers being provided with means for admitting fluid fuel thereto, substantially as specified. 110

3. A burner comprising a plurality of contiguous mixing chambers, pipes communicating with certain of said mixing chambers and having their upper portions extending outwardly, and pipes communicating with the other of said mixing chambers and being of greater height than said first-mentioned pipes, certain of said second-mentioned pipes being provided with upwardly extending branches, each of said mixing chambers being provided with means for admitting fluid fuel thereto, substantially as specified. 115 120

4. A burner comprising a plurality of contiguous mixing chambers, pipes communicating with certain of said mixing chambers and having their upper portions extending outwardly, and pipes communicating with 130

the other of said mixing chambers and being of greater height than said first-mentioned pipes, certain of said second-mentioned pipes being provided with laterally and upwardly extending branches, each of said mixing chambers being provided with means for admitting fluid fuel thereto, substantially as specified.

5. A burner comprising a plurality of contiguous mixing chambers, pipes communicating with certain of said mixing chambers and having their upper portions extending outwardly, and pipes communicating with the other of said mixing chambers and being of greater height than said first-mentioned pipes, certain of said second-mentioned pipes being provided with branches having their outlet openings in the plane of the outlet openings of the pipes to which they are connected, each of said mixing chambers being provided with means for admitting fluid fuel thereto, substantially as specified.

6. A burner comprising outer, intermediate, and central mixing chambers, pipes communicating with said outer mixing chambers and having their upper portions extending outwardly, pipes communicating with said intermediate mixing chambers and provided with laterally and upwardly extending branches, and pipes communicating with said central mixing chamber, said second and third mentioned pipes being of greater height than said first-mentioned pipes and having their outlet openings in the same plane, each of said mixing chambers being provided with means for admitting fluid fuel thereto, substantially as specified.

7. A burner comprising outer, intermediate, and central mixing chambers, pipes communicating with said outer mixing chambers and having their upper portions extending outwardly, pipes communicating with said intermediate mixing chambers and provided with laterally and upwardly extending branches, and pipes communicating with said central mixing chamber, said second and third mentioned pipes being of

greater height than said first-mentioned pipes, the outlet openings of said second and third mentioned pipes and the outlet openings of said branches being in the same plane, each of said mixing chambers being provided with means for admitting fluid fuel thereto, substantially as specified.

8. A burner comprising a hollow casting having top and bottom walls, side walls, and end walls, imperforate partitions within said hollow casting extending between the top and bottom walls thereof and forming a plurality of mixing chambers co-extensive in height with the height of said casting, each of said mixing chambers being provided with openings in its upper wall, pipes communicating with said openings, each of said mixing chambers being provided with a single inlet opening, and fuel supply pipes communicating with said several inlet openings whereby fuel may be admitted to any one of said chambers independently of the others thereof, substantially as specified.

9. A burner comprising a hollow casting having top and bottom walls, side walls, and end walls, imperforate partitions within said hollow casting extending between the top and bottom walls thereof and forming a plurality of mixing chambers co-extensive in height with the height of said casting, each of said mixing chambers being provided with openings in its upper wall, pipes communicating with said openings, each of said mixing chambers being provided with a single inlet opening in its bottom wall, and fuel supply pipes communicating with said several inlet openings whereby fuel may be admitted to any one of said chambers independently of the others thereof, substantially as specified.

Signed at the city of New York, in the county and State of New York, this 15th day of March, one thousand nine hundred and seventeen.

SEBASTIANO MARTOCCIO.
